UNITED STATES PATENT OFFICE.

LIONEL D. SAXTON, OF NEW YORK, N. Y.

SAFETY-RAZOR.

1,009,101.

Specification of Letters Patent. Patented Nov. 21, 1911.

Application filed October 28, 1910. Serial No. 539,525.

To all whom it may concern:

Be it known that I, LIONEL D. SAXTON, a citizen of the United States, residing in the borough of Manhattan, city, county, and 5 State of New York, have invented certain new and useful Improvements in Safety-Razors, of which the following is a specification.

This invention relates to safety razors and 10 its object is to provide for the use of a blade with a single cutting edge and no side notches, said blade to be held in place by spring pressure exerted from within the handle as will be more fully described in the 15 following specification set forth in the claims and illustrated in the drawings, wherein—

Figure 1 is a perspective view of the improved razor. Fig. 2 is a similar view showing the parts detached and from their lower sides. Fig. 3 is a vertical sectional view.

The razor comprises a hollow handle 5, of any desired outside design and having at its upper end a cross arm 6 rigidly secured thereto and with notches 7 at either end.

Into the hollow handle is fitted a stem 8 having at its outer end the guard plate 9 which holds the blade 10 in place against 30 the cap plate 14. This style of razor ordinarily is provided with a blade having notches at its ends, but the present invention is adapted to receive and carry a blade such as is shown in Fig. 2. The upper surface of the plate 9 is perfectly flat and plain, but it may be slightly inclined toward the guard teeth 13. The plate 9 has notches 18, at its opposite ends to permit the plate to be placed in position on the blade 10 after 35 the latter has been positioned on the cap plate 14 the lugs 15 passing through the notches in plate 9. When the blade is positioned on the cap plate 14, it is held by the guard plate 9, which has on its ends opposite to the guard teeth 13, projecting shoulders 11 which fit into the recesses 12 in the cap plate 14 to hold the guard plate in position. The cap plate has at either end depending lugs 15, turned inwardly toward 40 themselves to receive the outer ends of the cross arm 6, the notches fitting about the lugs so that the cross arm will not turn without pressure upon the handle 5. The cap

plate 14 is also provided with a flange, and shoulders 17 which hold the blade in the 55 proper relative position between the guard plate 9 and the cap plate 14. When the cross arm has been pressed down against the guard plate 9, the ends are swung around under the lugs, the pressure is released and 60 the spring in the handle 5 causes the notches 7 to engage the lugs 15. The blade is then firmly held between the two plates and the razor is ready for use.

I have secured in my invention a simply 65 constructed device of few parts, which can be easily and quickly taken apart and put together again when a blade is to be removed or inserted. This is an important feature in view of the fact that safety razor blades 70 are ordinarily stropped a number of times before they need to be honed.

It is obvious that the details of this razor may be otherwise arranged and modified without departing from the essential features above described.

What I claim as new and desire to secure by Letters Patent is:

1. In a safety razor the combination of the following elements; a cap plate having 80 depending sides with inwardly projecting ends, means adapted to position the blade comprising a flange on one edge of the cap plate and shoulders on the ends of the opposite edge of the cap plate and recesses adapted 85 to engage with shoulders on the guard plate; a blade sharpened on one edge; a notched guard plate having guard teeth on one edge and projecting shoulders adapted to engage with the said recesses in the cap 90 plate and a handle with locking means comprising a cross arm with notched ends adapted to engage with the inwardly projecting ends of the depending sides of the cap plate and rigidly confine the blade between the 95 cap plate and the guard plate.

2. In a safety razor, the combination of the following elements; a cap plate having depending sides with inwardly projecting ends, blade positioning shoulders and flange 100 and recesses adapted to engage with shoulders on the guard plate; a blade sharpened on one edge; a notched guard plate with a stem and with guard teeth on one edge and having projecting shoulders adapted to engage with the said recesses in the cap plate;

a hollow handle with a cross arm having notched ends adapted to engage with the inwardly projecting ends of the depending sides of the cap plate and a spring within 5 the handle adapted to hold the ends of the cross arm in engagement with the ends of the sides of the cap plate.

In witness whereof, I have hereunto set my hand this 17th day of October, 1910.

LIONEL D. SAXTON.
